DESIGN FOR A REFLECTOR SIGNAL DEVICE OR THE LIKE

John C. Haggart, Jr., Westfield, N. J., assignor
to Signal Service Corporation, a corporation
of Delaware

Application September 2, 1939, Serial No. 87,028

Term of patent 14 years

To all whom it may concern:

Be it known that I, John C. Haggart, Jr., a citizen of the United States and a resident of Westfield, in the county of Union and State of New Jersey, have invented a new, original, and ornamental Design for a Reflector Signal Device or the like, of which the following is a specification, reference being had to the accompanying drawing, forming part thereof.

The figure is a perspective view of a reflector signal device, showing my new device. The opposite sides of my reflector signal device are substantially the same in appearance as the sides disclosed.

I claim:

The ornamental design for a reflector signal device or the like, as shown and described.

JOHN C. HAGGART, JR.
